UNITED STATES PATENT OFFICE.

HERMAN N. PETERSEN, OF PEORIA, ILLINOIS.

IMPROVEMENT IN FLOUR-BOLTS.

Specification forming part of Letters Patent No. 122,054, dated December 19, 1871.

To all whom it may concern:

Be it known that I, HERMAN N. PETERSEN, of the city of Peoria, in the county of Peoria, in the State of Illinois, have invented a new and Improved Bolting Apparatus; and do hereby declare that the following is a full, clear, and exact description thereof, reference being had to the annexed drawing making a part of this specification, in which like letters of reference refer to like parts, and in which—

Figure 1 represents a perspective view of the bolt; Fig. 2, longitudinal section through *a a a a*, Fig. 3; and Fig. 3, an end view.

This bolt has circular heads or ends and corresponding circular stretchers in the interior—the ribs are all on the exterior—the whole of the bolting-cloth being by this plan applied to sifting the flour. The heads or ends of the bolt are screwed by rods in opposite directions when it is desired to tighten the cloth.

A A' represent the circular open ends or heads held concentrically to the shaft *B* by the arms *h* and cap *D*; *A* entrance-end, and *A'* exit-end for flour. The bolting-cloth is nailed to the edge of each head. *C C C C* are ribs or bars, to which the bolting-cloth is sewed. They run, as in the usual mode, longitudinally of the bolt, and are four in number, placed equidistant around the bolt, and inclosed in a canvas or muslin cover, to which the bolting-cloth *n n n* is sewed—that is, to that part of said cover on the under surface of the ribs, as may be seen in the end view of Fig. 3. These ribs are provided with thumb-screws *i* at the ends and at the intermediate circular stretchers *F*, which pass from the upper surface of rib through it and the cloth, and press on a plate, *k*, on the face of each head or end and intermediate circular stretcher or stretchers *F*, which are used to stretch the cloth *n n n* latitudinally between each rib *C C C*.

The following description of one end of apparatus will be sufficient, as the other end is but a modification of this. *D*, a metal cap, with a flange, *d*, near the plane of the head or end *A* and *A'*, the exterior of the socket being flush with the surface of shaft *B*, so as to permit the sliding hub *E* to pass freely thereon. The latter also carries a flange, *e*, in which are set the spokes or arm *h h*, which carry the bolt-head or end *A*; the extremities of each spoke is fixed to the head *A*.

A slot, *a*, in the hub *E* is filled with a screw or pin, *b*, to confine the hub *E*, and yet allow of a reasonable space for screwing it toward the end of shaft *B*. The latter is accomplished by means of two rods, *g g*, passing through the flanges of the cap *D* and sliding hub *E*, and fitted with nuts on the exterior surface of the cap *D*.

The operation of this invention is as follows: To stretch the cloth longitudinally of the bolt the rods *g g g g* at either end, connecting the flanges *d e* of the cap *D* and hub *E*, bring the head *A* further outward, stretching the cloth *n n n*. The ribs *C C C C*, to which are fastened the cloth, stretch the latter longitudinally by increasing (by pressure of screws *i i i* on plates *k k k*) the distance between said ribs and the heads *A-A'* and stretchers *F* and *c*—that is, enlarging the circle of the cloth. The latter may be removed for repairs by simply extracting the tacks at either end of bolt and the cloth will slip off.

The advantages of this device are as follows: By placing the ribs *C C C C* on the outside of the cloth *n n n n* and stretching the cloth on a circle, a continuous bolting surface is presented to the flour, instead of the usual or common plan, in which there are six sides to the bolt and interior ribs at each angle which carry up the unbolted flour more than one-half way, choking so much of the bolting-cloth, and then dumping said flour onto the bottom of the bolt, stretching and wearing the cloth, and particularly at those parts between the ribs. My plan offers a continuous surface to the flour, so that the cloth wears equally throughout, doing at least as much as one and a half times more work than the interior ribbed bolts, the cloth lasting at least half as much longer. Further, the No. 10 bolting-cloth when used on my apparatus separates the flour as white and as fine as the No. 12 (a finer cloth) does on the common bolting apparatus. Further, the cloth can be removed in a few moments by simply extracting the tacks, which is the only attachment between the cloth and the bolt-frame.

Having thus fully described my invention, what I claim therein as new, and desire to secure by Letters Patent, is—

1. The head *A*, adjustable sliding hub *E*, and spokes *h*, in combination with the cap *D*, screw-rods *g*, and shaft *B*, substantially as set forth.
2. The ribs *C*, provided with set-screws *i* for

stretching the cloth latitudinally, in combination with the heads A of a flour-bolt, constructed and arranged to operate substantially as set forth.

3. A circular flour-bolt, consisting of heads A A' and stretcher F, ribs C with set-screws i, shaft B, provided with adjustable sliding hubs E having spokes h for supporting the heads, and connecting with caps D on the ends of the shaft by screw-rods g, by which the said hubs are made adjust-

able for stretching the cloth, substantially as shown and set forth.

In testimony that I claim the foregoing improvement in flour-bolts I have hereunto set my hand this 29th day of August, A. D. 1871.

HERMAN N. PETERSEN.
